UNITED STATES PATENT OFFICE.

JOHN H. WOOLLIS CROFT, OF HAWARDEN, ENGLAND.

BRUSH-HOLDER FOR ELECTRICAL MACHINES.

No. 921,327.

Specification of Letters Patent.

Patented May 11, 1909.

Application filed November 20, 1908. Serial No. 463,691.

To all whom it may concern:

Be it known that I, JOHN HAROLD WOOLLIS CROFT, A. M. I. E. E., subject of the King of Great Britain, residing at Hawarden, in the county of Flint, Wales, England, have invented certain new and useful Improvements in and Connected with Brush-Holders for Electrical Machines, of which the following is a specification.

This invention has for its object the production of a brush holder for electrical machines, which while possessing the desirable quality of providing a light, and adjustable mounting of the brush with small inertia of the moving parts, shall be more simple in construction and more cheap to manufacture than the brush holders at present in use.

The device, as is usual in brush holders, comprises two arms or sets of arms, one set adapted to be rigidly fixed, and the other set movably mounted and adapted to apply pressure to the carbon or other brush, a spring member being arranged in between these two arms or sets of arms or relatively thereto so as to provide the necessary pressure.

According to the present invention these arms and the device for attaching them to the bar of the brush rigging, are made of wire bent to the desired form. The device for attaching the fixed arm or arms to the bar, is formed by bending the wire into a loop or loops, which encircles the bar, and providing a pivoted link (or chain links) and toggle device, for tightening up the coil and so clamping the loop.

In order that the invention may be more clearly understood, it will now be described with reference to the accompanying drawings, in which:—

Figure 1 is a side elevation of a brush holder in position; Fig. 2, a plan thereof; Figs. 3 and 4, corresponding views showing a modification; Fig. 5, a side elevation of a modified part of the holder; and Figs. 6 and 7, side elevation and plan respectively showing a method of mounting the brush in the holder.

In the forms shown a carbon block *a* is used as the brush, and is mounted with a sliding fit in a loop *b* formed by bending a piece of wire to the shape of the block. The two ends of this loop are then brought together and used to form the fixed bar *c*, being carried back for the desired distance at

which the brush is to be fixed from the bar. At this point the two ends of the wire are bent back upon themselves, forming an eye *d*. Then the two ends of the wire are separated slightly and coiled around into circular loops *e* of slightly larger size than the bar *f* upon which the holder is to be mounted. At the ends of these coils the wires terminate in eyes *g*. The toggle device for tightening up these coils so as to grip the bar, is formed of two members *h* and *k*; one of these, *h*, engages with one end of the eye *d*, formed at the commencement of the coils *e* as above mentioned, while the other end is engaged by the second member *k*. This latter is formed as a **U** piece the ends of the arms of which engage the eyes *g* at the ends of the coils *e*.

The member *h* is pivotally connected to the member *k* by means of eyes *m* or the like at about half way along the arms of the **U**. The end of the **U** serves as the handle which is moved when it is desired to tighten up or loosen the clip. The two members *h* and *k* are so proportioned that when the second member is moved over into one position, the two ends of each coil *e* are brought slightly nearer together, thus causing the coils to decrease slightly in diameter, and grip the bar *f* upon which they are placed.

The movable arm *n* which applies the pressure to the brush *a* is formed as a **U** shaped member, the middle part of which presses upon a groove in the top of the carbon block. The ends of the said member are formed as eyes or loops *e* to engage either around the bar of the rigging or (as shown) some part of the holding clip. The necessary pressure to the carbon brush is supplied by means of a spring *p* located between the fixed and the movable bars, *c* and *n*, being attached to the latter by the intermediary of a bridge piece *q* which straddles the **U**. This bridge piece is preferably mounted so as to be movable along the arms so as to adjust the pressure and leverage of the spring, notches *r* being provided to retain the bridge in position.

A good conducting contact between the brush and the holder is provided by means of a flexible metallic connection *s*, one end of which is conductively secured to the block, while the other end engages with some part of the fixed arm *c*.

It will be seen that the form of clip above

described, has the advantage of being instantaneously fixed or released without any tool being necessary. If, for instance, it is desired to take one brush holder out of operation, so as to permit examination or change of brush, it is simply necessary to operate the toggle device to loosen the coil, turn the holder up so as to raise the brush from the commutator or slip ring, and fasten the clip 10 again and secure the holder in that position, or instead of operating the toggle device simply raise the pressure arm and draw the brush out of the loop *b*; if desired holding the brush by placing one end against the outer 15 transverse part of the loop and the other end against the pressure arm.

My holder also provides what is required in a good brush holder, namely lightness and ability to conform to and keep in direct contact with the rotating commutator or slip ring of electrical machines. The lightness of the moving parts of the holder allows the brush to readily conform or give, to follow any vibration or peculiarities of the commutator, and is particularly suited for high 25 speed machines. I obtain by my invention lightness and cheapness of manufacture. It being entirely or mostly made of wire, castings for the most part are done away with. Furthermore the loop or retaining box for the brush being of wire, or if preferred of a metallic stamping, there is very little friction between the brush and the loop or box, which is made of small section just sufficient 30 to retain the brush, and amply carry current from the brush by means of the flexible pigtail, thereby being in direct metallic contact with the brush rigging arm.

It will be obvious that although the device 40 has been described in considerable detail, the invention is not limited to the precise construction mentioned. For instance, it is not essential that a carbon block shall be used for the brush, although in the majority of cases it is considered the more suitable form. Again, it is not essential that the brush should be supported in a guide loop carried by the fixed arm. The brush may be entirely fixed by means of the movable arm 45 (see Fig. 5), the fixed arm *c* simply serving as a support for one end of the pressure spring *p*. As shown in Fig. 5, when a carbon block *a* is used for the brush, this may be attached to the arms *n* which support it, by 50 forming holes in the sides of the block, into which the ends *w* of the supporting arms *n* engage or are trunnioned, an arrangement such as horizontal grooves *x* in the block in which the arms *n* also engage being provided 55 to hold the brush against turning on the trunnions and a flexible metallic connection *s* taken from the center of the carbon, to the fixed arms *c*.

As shown in Figs. 6 and 7, the brush *a* may 60 be connected to the pressure arm *n* and to

the flexible conductor *s* by means of a metallic cap *y* which springs tightly over the upper end of the brush, and, if desired, fit into a transverse groove *z* formed therein, lugs *2* being provided for securing to the pressure 70 arm *n* and a clip *3* for attachment to the conductor *s*. In this case when it is desired to change a brush it is simply necessary to withdraw it from the cap *y* and insert another in its place.

If desired the bridge piece can be of fiber or any suitable insulating material, so that tension can be put upon the brush, when the machine is running, and the said bridge piece so arranged, that it can be rocked or 80 walked forward to adjust the position of the spring, thus giving different pressures or leverage to the carbon brush.

The spring instead of being of the kind hereinbefore described can (as shown in Figs. 85 3 and 4), be a helical spring *t* formed with a projecting arm *u* in one with it, this arm being coupled by a link *v* to the fixed arm *c*, which link is either fixed in position on the arm or sliding thereon.

The fixed arm with the loop for the sliding brush, can be fitted or provided with a gage or distance pin if desired, to determine that the loop shall always be brought back to the same position to which the brush was 90 initially bedded. This pin can be of ivory or other suitable insulating material, and placed at any convenient part of the fixed arm, either in front or behind the brush. By this device, the distance the arm has to 95 be brought into proximity with the commutator is gaged, and so I insure that the brush holder after being disturbed, shall be brought back to the same position as before.

I declare that what I claim is:—

1. A brush holder for electrical machines comprising a member adapted to encircle the brush bar, a toggle device for tightening said member on said bar, brush supporting means attached to said member and means for applying pressure to the brush.

2. A brush holder for electrical machines comprising a member adapted to encircle the brush bar, a toggle device for tightening said member on the bar, a pair of members, one 110 rigidly attached to said encircling member and the other pivotally mounted relative thereto, adapted to support the brush, and means for applying pressure to the brush.

3. A brush holder for electrical machines 120 comprising a member adapted to encircle the brush bar, a toggle device for tightening said member on the bar, a pair of members one rigidly attached to said encircling member and the other pivotally mounted relative 125 thereto, adapted to support the brush, and a spring device connecting said pair of members.

4. A brush holder for electrical machines comprising a member formed of wire coils 130

adapted to encircle the brush bar, a toggle device for tightening the member on the bar, a member formed by a continuation of the wire coils of the encircling member and extending outwardly therefrom, a second outwardly extending member pivotally mounted relative to the first member and a spring connection between these two outwardly extending members, said two members thus connected serving as means for supporting and applying pressure to the brush.

5. A brush holder for electrical machines comprising a member adapted to encircle the brush bar, a toggle device for tightening the member on the bar consisting of two parts pivotally connected with the two ends of the encircling member and also pivotally connected together and one prolonged past the point of connection to form a handle; 10 brush supporting means attached to said encircling member and means for applying pressure to the brush.

6. A brush holder for electrical machines comprising a member adapted to encircle the brush bar, said member being formed of wires which are bent upon themselves to form an eye and then coiled into loops; a toggle device for tightening said member upon the bar engaging the ends of the coils 25 and the eye; brush supporting means attached to said encircling member and means for applying pressure to the brush.

7. A brush holder for electrical machines comprising a member formed of wires bent back upon themselves to form an eye and then coiled into loops adapted to encircle the brush bar; a toggle device for tightening the member on the bar consisting of two parts pivotally connected with the ends of the 30 coils and the eye respectively and also pivotally connected together and one prolonged past the point of connection to form a handle; brush supporting means attached to said encircling member and means for applying pressure to the brush.

8. A brush holder for electrical machines comprising a member formed of wires bent back upon themselves to form an eye and then coiled into loops adapted to encircle the brush bar, a toggle device for tightening the encircling member on the bar, a member formed by a continuation of the wires which form the eye and extending outwardly from the encircling member, a second outwardly extending member pivotally mounted relative to the first member and a spring connection between these two outwardly extending members, said two members thus connected serving as means for supporting and applying pressure to the brush.

9. A brush holder for electrical machines comprising a member adapted to encircle the brush bar, a toggle device for tightening the member on the bar consisting of two parts each formed of a piece of wire bent

into approximately U-shape, one of these U-shaped pieces engaging one end of the encircling member by the ends of its arms, while the other U-shaped piece engages with its central part the other end of the encircling member, the two ends of this latter U-shaped piece being engaged by loops in the arms of the first mentioned U-shaped piece, the middle part of which serves as a handle; brush supporting means attached to the encircling member and means for applying pressure to the brush.

10. A brush holder for electrical machines comprising a member formed of wire coils adapted to encircle the brush bar, a toggle device for tightening said member on the bar consisting of two parts each formed of a piece of wire bent into approximately U-shape, one of these U-shaped pieces engaging the wire coils at one end by the ends of its arms, while the other U-shaped piece engages with its central part the other ends of the coils, the two ends of this latter U-shaped piece being engaged by loops in the arms of the first mentioned U-shaped piece, the middle part of which serves as a handle; brush supporting means attached to the encircling coils and means for applying pressure to the brush.

11. A brush holder for electrical machines comprising a member adapted to encircle the brush bar formed of wires which are bent upon themselves to form an eye and then coiled into loops, a toggle device for tightening the member on the bar consisting of two parts each formed of a piece of wire bent into approximately U-shape, one of these U-shaped pieces engaging the ends of the coils by the ends of its arms, while the other U-shaped piece engages with its central part the eye, the two ends of this latter U-shaped piece being engaged by loops in the arms of the first mentioned U-shaped piece, the middle part of which serves as a handle; brush supporting means attached to the encircling member and means for applying pressure to the brush.

12. A brush holder for electrical machines comprising a member adapted to encircle the brush bar, a toggle device for tightening said member on the bar, a pair of members, one rigidly attached to said encircling member and the other pivotally mounted relative thereto, adapted to support the brush, a spring connection firmly attached to one of said pair of members and adjustably connected with the other said pair of members.

13. A brush holder for electrical machines comprising a member formed of wire coils adapted to encircle the brush bar, a toggle device for tightening said member on the bar, a member formed by a continuation of the wire coils of the encircling member and extending outwardly therefrom, a second outwardly extending member pivotally

mounted relative to the first member, a spring connection firmly attached to one of said outwardly extending members and connected to the other of said members by means of a part which is adjustable along said member.

14. A brush holder for electrical machines comprising a member formed of wire coils adapted to encircle the brush bar, a toggle device for tightening said member on the bar, 10 a member formed by a continuation of the wire coils of the encircling member and extending outwardly therefrom, and having at its outer end a loop adapted to receive and 15 serve as a guide for the brush, a second outwardly extending member pivotally mounted relative to the first member, and a spring connection between these two members.

15. A brush holder for electrical machines 20 comprising a member formed of wire coils adapted to encircle the brush bar, a toggle device for tightening said member on the bar, a member formed by a continuation of the wire coils of the encircling member and 25 extending outwardly therefrom, and having at its outer end a loop adapted to receive and serve as a guide for the brush, a second outwardly extending member pivotally mounted relative to the first member and adapted 30 to press with its outer end upon a brush sliding in the loop of said first member, and a spring connection between these two members.

16. A brush holder for electrical machines 35 comprising a member formed of wire coils adapted to encircle the brush bar, a toggle device for tightening said member on the bar, a member formed by a continuation of the wire coils of the encircling member and 40 extending outwardly therefrom and having at its outer end a loop adapted to receive and serve as a guide for the brush, a second outwardly extending member pivotally mounted relative to the first member and formed of 45 a U-shaped piece of wire, the center of which is adapted to bear on a brush mounted in the loop of the first member, and a spring connection between these two members.

17. A brush holder for electrical machines 50 comprising a member formed of wire coils adapted to encircle the brush bar, a toggle device for tightening said member on the bar, a member formed by a continuation of the wire coils of the encircling member and 55 extending outwardly therefrom and having at its outer end a loop adapted to receive and serve as a guide for the brush, a second outwardly extending member pivotally mounted relative to the first member and formed of 60 a U-shaped piece of wire, the center of which is adapted to bear on a brush mounted in the loop of the first member, a bridge piece mounted on the arms of said U-shaped member and a spring connection between said

bridge piece and the first mentioned outwardly extending member.

18. A brush holder for electrical machines comprising a member formed of wire coils adapted to encircle the brush bar, a toggle device for tightening said member on the bar, 70 a member formed by a continuation of the wire coils of the encircling member and extending outwardly therefrom and having at its outer end a loop adapted to receive and serve as a guide for the brush, a second outwardly extending member pivotally mounted relative to the first member and formed of a U-shaped piece of wire, the center of which is adapted to bear on a brush mounted in the loop of the first member, a bridge piece extending between the arms of said U-shaped member and adjustable thereupon, a spring connection between said bridge piece and the first mentioned outwardly extending member.

19. A brush holder for electrical machines comprising a member adapted to encircle the brush bar, a toggle device for tightening said member on the bar, a member rigidly attached to said encircling member and extending outwardly therefrom and formed at its outer end as a loop adapted to serve as a guide for the brush, a second outwardly extending member pivotally mounted relative to said encircling member, a spring connection between said two outwardly extending members, a metal cap adapted to fit tightly over the end of the brush and to receive the end of the pivotally mounted member and an electrically conducting connection between said cap and said fixed outwardly extending member.

20. A brush holder for electrical machines comprising a member adapted to encircle the brush bar, a toggle device for tightening said member on the bar, a member rigidly attached to said encircling member and extending outwardly therefrom and formed at its outer end as a loop adapted to serve as a guide for the brush, a second outwardly extending member pivotally mounted relative to said encircling member, a spring connection between said two outwardly extending members, a metal cap adapted to fit tightly over the end of the brush and attached to the outer end of the pivotally mounted member, and a conductive connection between said cap and said fixed outwardly extending member.

21. A brush holder for electrical machines comprising a member adapted to encircle the brush bar, a toggle device for tightening said member on the bar, a member rigidly attached to said encircling member and extending outwardly therefrom and formed at its outer end as a loop adapted to serve as a guide for the brush, a second outwardly extending member pivotally mounted relative to said encircling member, a spring connec-

tion between two said outwardly extending members, a metal cap adapted to fit tightly over the end of the brush and formed with a groove to receive the outer end of said pivotally mounted member and a conductive connection between said cap and said fixed outwardly extending member.

In witness whereof, I have hereunto signed my name this 11 day of Novr. 1908, in the presence of two subscribing witnesses.

JOHN H. WOOLLISCROFT.
